Attorney, Agent, or Firm—J. Wesley Blumenshine; John M. Pollaro; Richard C. Witte

CLAIM

The ornamental design for an inner pack bottle carrier, as shown and described.

DESCRIPTION

FIG. 1 is a top plan view of an inner pack bottle carrier embodying our new design;

FIG. 2 is a right side elevational view thereof; and

FIG. 3 is a front elevational view thereof.
The bottom plan, left side elevational, and rear elevational views of the embodiment of FIG. 1 are not shown and are identical to the top plan, and right side and front elevational views shown in FIGS. 1 through 3, respectively.
